GOVERNOR FOR FLUID MOTORS

Paul Van Sittert, Cleveland Heights, Ohio, assignor to The Cleveland Pneumatic Tool Company, Cleveland, Ohio, a corporation of Ohio

Application April 28, 1937, Serial No. 139,537

5 Claims. (Cl. 121—34)

This invention relates broadly to fluid actuated motors, but more particularly to a speed-governor for fluid actuated rotary motors.

The main object of this invention is to provide 5 a speed governor for portable fluid actuated motor such as grinders and the like, with means adjustable for selectively controlling the free speed of the motor.

Another object of this invention is to produce 10 a speed governor of simple construction forming a compact assembly which is strong, durable and efficient.

Another object of this invention is to produce 15 a speed governor for fluid actuated rotary motors which is readily accessible for inspection or replacement, which is not likely to leak air or have its operation affected by wear, and which is so constructed as to be sensitive to changes of speed.

Other objects of this invention will be apparent 20 from the following detailed description wherein in similar characters of reference designate corresponding parts and wherein:

Fig. 1 is a longitudinal sectional view of a fluid actuated motor embodying the invention.

Fig. 2 is an enlarged sectional view illustrating 25 the governor.

Referring to the drawing, 10 represents a main housing having a stationary cylinder 11 disposed therein and formed with a rotor-chamber 12, which chamber accommodates the usual rotor 13 carrying blades 14. Keyed to the rotor 13 by a key 13a, there is a rotor shaft 15 depending from the housing 10 to receive a cutting tool such as a grinding wheel 16, which is secured thereon 35 in the usual way between a washer 17 and a nut 18. Within the lower part of the housing 10, the shaft 15 is journaled within a ball bearing 19, which is secured in position by a nut 20.

Extending through the upper end of the housing 40 10, there is the shafted end portion 21 of the rotor 13, which end is also journaled within a ball bearing 22 secured in position by a nut 23. The shafted end portion 21 is internally threaded to receive an extension 24, which is mounted coaxially with the rotor 13 for rotation therewith. This extension protrudes into a chamber 25 formed within the motor cover 26, which is secured to the housing 10 by one or more bolts 27.

Rigidly secured to the housing 10 and extending 50 laterally therefrom in opposite direction, there are two handles 28 and 29. The handle 29 is preferably made of a casting having different passages cored therein and including an inlet passage 30 terminated at its outer end by a threaded connection 31. This passage is con-

trolled by a throttle valve 32 slidably mounted within a bushing 33, which bushing is held in position by a screw threaded plug 34. The interior of the bushing 33 is in communication with the passage 30 through ports 35, while the throttle valve is always urged in closed position by a compression spring 36. To actuate the throttle valve, there is provided the usual mechanism including a rotatable handle 37 carrying, in eccentric relation with the rotary axis thereof, a roller 38 which 10 engages one end of a slidable pin 39 having its other end resting on the throttle valve 32.

Referring now more particularly to the present invention, it will be seen that within the cover 26 there is a speed governor including the extension 24 which is formed with integral arms 40 extending laterally therefrom, and each carrying a bell-crank weight 41 pivotally mounted thereon by a pin 42. These weights have their inner end resting on an annular shoulder 43 formed on a 15 governor-controlled valve 44 which has one end slidably guided within a counterbore 24a formed in the extension 24, while the other end thereof forms a head or a metering portion 45. Screwed within the cover 26 and disposed coaxially with the valve 44, there is a bushing 46 having a head 47 extending outside of the cover and formed with two holes 48 adapted to receive a wrench through which the bushing may be rotated. Below the head 47, within a counterbore provided 20 within the cover 26, there is a locking spring 49 for holding the bushing against accidental rotation. The bushing extends through an annular groove 50 cored within the cover 26, and has its inner end turned smooth for fluid tight engagement with the inner wall of a bore 51 extending 30 from the chamber 25 to the groove 50. Internally, the bushing is provided with a counterbore 52 opening into the chamber 25 through a relatively short bore 53, and in constant communication with the annular groove 50 through radial ports 54. The short bore 53 is of a diameter substantially equal to that of the head 45 of the valve 44, which head is constantly urged 35 away from the bore 53 by a compression spring 55 located within the extension 24 and acting on the valve 44. Extending through the valve 44, there is a small port 56.

Leading from the throttle valve 32 into the annular groove 50, there is an inlet passage 57, 50 and from the chamber 25 into the cylinder 11, there is another passage 58. From this last passage, the motive fluid may be admitted into the rotor chamber 12 through a plurality of inlet ports 59.

In the handle 28 there is also provided a lubricant reservoir 60, from which lubricant is admitted into the passageway 30 through a lubricant-regulator generally designated by 61.

5 In the operation of the motor, motive fluid is admitted into the passageway 30 from a motive fluid conveying conduit (not shown) secured to the handle 28 through the connection 31. The throttle valve is then opened by manually rotating its component handle 37, thereby admitting motive fluid into the annular groove 50 via the passage 51. In this instance, that is when the motive fluid is first admitted into the groove 50, the governor-valve 44, due to the effort of the compression spring 55, will assume the position shown in Fig. 1. In this extreme open position of the governor-valve, the weights 41 are engaging the outer wall of the extension 24 to prevent further opening movement of the valve. 10 The motive fluid admitted into the groove 50 is now free to flow therefrom into the chamber 25 via the bore 53, from where it is admitted into the rotor-chamber 12 through the passage 58 and ports 59. Once in the rotor-chamber 12, the motive fluid will act on the blades 14 for imparting rotation to the rotor in the usual manner well known by those skilled in the art.

In practice, to meet the well known safety requirements, a motor of a given size can not exceed a predetermined or prescribed speed which is generally termed free speed and is understood to mean the maximum rotary speed of the rotor-shaft 15 taken when the motor is actuated without load or torque resistance normally resulting from the tool 16 engaging the work. Heretofore, due to manufacturing tolerances, it was difficult and expensive to produce fluid actuated rotary motors which would meet the free speed requirement, thus resulting in motors having a maximum free speed well below that prescribed. In the present construction, as the speed of the rotor increases, the lower portion of the weights 41 swings outwardly causing the inner end of the bell-crank-weights to swing inwardly for moving the valve 44 against the compression spring 55 until the lower end of the valve engages the bottom of the counterbore 24a formed within the extension 24. In this instance, the motive fluid conveying bore 53 between the groove 50 and the chamber 25, that is, the annular clearance between the inner edge of the bore 53 and the corresponding edge of the valve-head 45, has an effective conveying capacity calculated to result in a free speed of the motor well below that prescribed. However, by turning, or more specifically screwing the bushing 46, the annular space between the inner edge of the bore 53 and the head 45 of the valve 44 may be increased until the motor reaches the prescribed free speed.

50 When the cutting tool 16 is applied to the work, it will transmit a torque resistance to the rotor tending to retard the speed of the motor. In this instance the spring 55 acting on the valve 44 will gradually open the latter relative to the bore 53 for maintaining the speed of the motor substantially constant.

Due to the port 56 provided through the valve 44, the motive fluid admitted into the bushing-counterbore 52 and acting on the upper end of the valve, will flow through the port 56 to act on the other side of the valve to nullify the action of the motive fluid on the valve. However, the flow of the motive fluid between the head 45 of the valve 44 and the adjacent edge of the bore 53 will create a suction tending to move the valve

against the spring 55, thus cooperating with the centrifugal force of the weights 41 for effecting the closing movement of the valve relative to the bore 53.

5 From the foregoing explanation, it will be understood that the invention provides a fluid actuated rotary motor equipped with a simple device through which the free speed of the motor may be controlled or adjusted from the exterior of the motor, and that through this device the free speed prescribed for a motor of a given size may readily be obtained without necessitating undue accuracy in the manufacture of the controlling parts.

10 It will also be understood that due to the novel design of the speed governor and its component valve, the action of the governor is not affected by wear of its moving parts. In the present construction, the head or metering portion 45 of the valve 44 is moved toward or from the bore 53 for 15 controlling the motive fluid conveying capacity of the passageway admitting motive fluid into the rotor-chamber 12. This passageway includes the space between the head 45 of the valve 44 and the inner edge of the bore 53, and since the head 20 45 does not engage the bushing 46, the head 45 is not subjected to wear affecting the control of the motive fluid conveying passageway.

25 Although the foregoing description is necessarily of a detailed character, in order to completely set forth the invention, it is to be understood that the specific terminology is not intended to be restrictive or confining and it is to be further understood that various rearrangements of parts and modifications of structural detail may 30 be resorted to without departing from the scope or spirit of the invention as herein claimed.

35 I claim:

1. A fluid actuated rotary tool including a housing, a rotor rotatable within said housing, a passage conveying motive fluid to said rotor, a duality of movable spaced elements cooperating with each other for controlling said passage, means responsive to the speed of the rotor and acting on one of said elements for partially closing said 40 passage, and means associated with the other of said elements for opening said passage irrespective of the position of said first mentioned element.

45 2. A rotary motor including a housing having a fluid actuated rotor rotatable therein, a duality of longitudinally spaced elements within said housing, the longitudinal space between said elements constituting a passage conveying motive fluid to the rotor for actuating the same, one of said elements being movable relative to the other for controlling the motive fluid conveying capacity of said passage, and means responsive to the 50 rotary speed of said rotor for automatically effecting the movement of said element.

55 3. A rotary motor including a housing having a fluid actuated rotor rotatable therein, means within said housing conveying motive fluid to the rotor for actuating the same including a passage, a valve, a head on said valve constantly spaced axially from one end of said passage cooperating therewith and axially movable relative thereto for controlling the motive fluid conveying capacity of said passage, and means responsive to the 60 rotary speed of said rotor for automatically effecting the axial movement of said valve and head.

70 4. A rotary motor including a housing having a fluid actuated rotor rotatable therein, a passage within said housing conveying motive fluid to the rotor for actuating the same, a valve-bushing ex- 75

5 tending into said passage, and a governor-controlled valve spaced from said bushing and co-operating therewith for automatically controlling said passage, said bushing being adjustable from the exterior of said housing for increasing the motive fluid conveying capacity of said passage irrespective of said valve.

5. A rotary motor including a housing having a fluid actuated rotor rotatable therein, a valve-
10 bushing within said housing, a passage through

said bushing conveying motive fluid to said rotor for actuating the same, a governor-controlled valve having a head spaced from said bushing and movable toward and from said passage for controlling the motive fluid conveying capacity thereof, said bushing being adjustable from the exterior of said housing for increasing the motive fluid conveying capacity of said passage irrespective of said valve. 5
